AUTOMOBILE LUG WRENCH

Normand L. Chapdelaine, 124 Olympic Ave.,
Woonsocket, R.I. 02895

Continuation-in-part of design application Ser. No. 14,431,
Nov. 13, 1968. This application Mar. 19, 1969, Ser.
No. 16,322

Term of patent 14 years

Int. Cl. D8—02

U.S. Cl. D8—26

FIG. 1

FIG. 2

FIG. 3

FIG. 1 is a perspective view of an automobile lug wrench, showing my new design;

FIG. 2 is a side elevational view thereof; and,

FIG. 3 is a rear elevational view thereof.

This is a continuation-in-part of my design application Ser. No. D. 14,431, filed Nov. 13, 1968, now abandoned.

I claim:

The ornamental design for an automobile lug wrench, as shown.
